Res. 366

Samuel W. Gibbs of Albany, N.Y. Ass't to
Jagger, Headwall & Perry, of Albany, N.Y.
Letters Patent No. 366 Dated April 8, 1851.

The Schedule referred to in these Letters Patent and making part of the same.

To whom it may concern:

Be it known that I, Samuel W. Gibbs, of the City of Albany and State of New York, have produced a new ornamental design for a Cooking Stove, and I do hereby declare that the annexed and accompanying drawings, are full and accurate delineations of the ornamented parts of said stove, with their several ornaments, the side plate, not represented in the drawing, being similar to and symmetrical with the side plate shown; and where portions of the plates are shown in the drawings, the portions not shown, with their ornaments, being similar to and similarly and symmetrically ornamented with the portions shown.

What I claim as my production, and desire to secure by Letters Patent, is the combination and arrangement of ornamental figures and forms, represented in the accompanying drawings, forming together an ornamental design for a Cooking Stove.
